UNITED STATES PATENT OFFICE

FREDERICK A. BALLOU, OF NAYATT, AND ROGERS T. STAFFORD, OF EAST PROVIDENCE, RHODE ISLAND, ASSIGNEES TO B. A. BALLOU & CO., INC., OF PROVIDENCE, RHODE ISLAND, A CORPORATION OF RHODE ISLAND

SHOE STRAP

Application filed April 13, 1928. Serial No. 269,837.

This invention relates to a shoe strap of the type more particularly adapted to be worn in connection with a slipper or opera pump provided with an instep strap; and 5 has for its object to provide a strap which will assist in holding the shoe in place on the foot of the wearer and at the same time not cause discomfort to the foot.

A further object of the invention is the 10 provision of a strap which will extend from the forward margin of the foot opening to an instep strap extending across from one edge of the shoe to the other with means for detachably connecting the ends of the strap 15 to the forward margin of the foot opening and to the instep strap whereby the same may be completely detached to permit the shoe to be worn without the strap, if desired.

A still further object of the invention is 20 the forming of a shoe strap extending from the forward edge of the foot opening to the instep strap which shall be elastic to permit of 25 yieldingly longitudinal extension of the strap itself and movement of the instep strap to which it is connected to better conform to 30 the muscular action of the foot in walking, dancing or the like.

The invention further consists in the provision of a strap of the type above mentioned 35 which is highly ornamental in appearance to dress up and add to the attractive features of the foot and shoe when worn in connection therewith.

With these and other objects in view, the 40 invention consists of certain novel features of construction, as will be more fully described, and particularly pointed out in the appended claims.

In the accompanying drawings:

Figure 1 is a perspective view of a shoe showing the strap attached thereto.

Figure 2 is a plan view of the back of the connecting strap showing one end engaging 45 the instep strap of the shoe.

Figure 3 is a side elevation of the construction shown in Figure 2.

Figure 4 is a view similar to Figure 2 showing a modification of the attaching means for securing the connecting strap to 50 the instep strap.

Figure 5 is a view similar to Figure 4 showing a modification in the strap itself between its attaching clips at its ends.

Figure 6 is a still further modification illustrating the connecting strap in conjunction with a metallic elastic instep strap with 55 an ornament at its center.

Figure 7 is a sectional view through the ornamental portion of the strap shown in 60 Figure 6.

In foot wear especially of the slipper or opera pump type, considerable difficulty is often experienced in properly securing the shoe on the foot to prevent slipping at the 65 heel and at the same time affording proper comfort to the foot of the wearer; and in order to assist in securing a shoe of this type in position and at the same time ornament the shoe and the foot of the wearer, we have 70 constructed an ornamental strap for connecting the instep strap of the shoe to the forward margin of the foot opening, which strap is elastic or yielding and extendible to exert 75 a forward elastic strain on the instep strap to assist in holding the heel of the shoe in place. The strap is provided with attaching means at its ends so constructed as to engage the instep strap or the forward margin of the shoe opening at any desired point and so be completely disconnected to allow the shoe to be worn without the strap when desired; and the following is a detailed description of the present embodiment of this invention illustrating means by which these advantageous results may be accomplished:

With reference to the drawing, 10 designates a shoe of the slipper or opera pump type having a foot opening 11. Some shoes of this type are provided with an instep 90

strap 12 formed integral with the upper of the shoe on one side to extend from one edge 13 thereof to the opposite edge 14 to be secured in place by any suitable connection. In other shoes of this type which are not made with an instep strap the same may be supplied by an instep strap 15 of the type illustrated in Figure 6 and as more fully disclosed in our Patents #1,640,104, August 23, 1927 and #1,660,215, February 21, 1928.

The connecting strap 16 illustrated in Figure 1 extends from the instep strap 12 to the forward margin 17 of the foot opening and is suitably connected thereto by means permitting complete detachment of the strap therefrom. We have found that a clip 18 having a body 19 forming one jaw and a lever arm 20 forming the other jaw, which jaws are resiliently pressed together, is a suitable connection for the strap 16 to the forward edge of the foot opening. A spur 21 is provided and carried by the arm 20 for engagement with the inside of the margin of the shoe to assist in securing the same thereto. The opposite end of the connecting strap is provided with some suitable means to engage the instep strap to which it is desired to be connected. If the instep strap is of the common leather type which is a part of the shoe upper as above referred to, we find it desirable to provide an ornamental part 22 which has a part 23 formed as a hook to extend over the instep strap 12. A portion 24 of this hook forms a means to resist the longitudinal pull of the connecting strap and tends to retain it against separation from the instep strap.

In other instances, the attaching means for the instep strap may be as illustrated in Figure 4, which is similar to the clip 18 above referred to, and consists of the parts 43 and 44 for engaging the outer and inner surfaces of the instep strap while a spur 25 acts as a portion to resist the longitudinal pull of the connecting strap and assists in prevention against separation from the instep strap. In both of which cases, however, it will be apparent that the connecting strap may be completely disconnected from the instep strap or connected thereto without the necessity of sewing shoe buttons or any other securing means to the shoe.

This connecting strap may be disconnected from the ornamental part 22, as illustrated in Figures 2 and 3, by means of a hook 26 having a closing tongue 27 which engages a loop 28 carried by the attaching means for the instep strap.

The connecting strap is formed of a series of units 29 each consisting of two relatively slid able parts 30 and 31, as illustrated in Figure 7, with a spring 32 between them tending to move the sliding parts to contracted position, by which formation an

elastic strap is formed for the purposes hereinbefore mentioned.

In other instances, the strap may be of mesh fabric 33 which is of itself somewhat yielding and may have additional provisions therefor in increasing the yielding effect thereof such for instance as springs 34 extending longitudinally thereof. 70

In utilizing the strap which is the subject of the patents above mentioned, we provide a part 35 intermediate the ends thereof which may be in the form of an ornament, as illustrated in Figure 6, if desired, and which carries a loop 37 to which a hook such as 26 may be suitably attached for releasably securing the connecting strap thereto. 75

The attaching clip 18 may be suitably ornamented by means of wings 38 as illustrated in Figure 6, where desired, and the surface of the connecting strap may be jeweled, engraved, enameled or otherwise highly embellished and ornamented to form the same attractive appearance. 85

The foregoing description is directed solely towards the construction illustrated, but we desire it to be understood that we reserve the privilege of restoring to all the mechanical changes to which the device is susceptible, the invention being defined and limited only by the terms of the appended claims. 90

We claim:

1. In combination, a shoe having a foot opening with an instep strap extending across from one side of the shoe to the other, a connecting strap extending from the forward edge of the foot opening to said instep strap, means for detachably securing the connecting strap to said instep strap, and means for detachably securing said connecting strap to the forward edge of said foot opening. 100

2. In combination, a shoe having a foot opening with an instep strap extending across from one side of the shoe to the other, a connecting strap extending from the forward edge of the foot opening to the said instep strap, releasable attaching means for securing the connecting strap to the instep strap and margin of the foot opening consisting of parts engaging the outer and inner surfaces of said instep strap and margin of the foot opening with portions positioned to engage other surfaces thereof to resist a longitudinal pull on said connecting strap tending to separate it therefrom. 110

3. In combination, a shoe having a foot opening with an instep strap extending across from one side of the shoe to the other, a connecting strap extending from the forward edge of the foot opening to said instep strap 120 consisting of a plurality of units some of which are yieldingly extendible to form an elastic strap, and a securing clip at the forward end for engaging the forward margin of the foot opening, and means at the other 125

130

end for detachably securing to the instep strap.

4. Ornamentation for a shoe having an instep strap extending across from one side of the shoe to the other comprising a connecting strap provided with ornamentation over its top surface and means for connecting said strap at each of its ends respectively to said instep strap and to the forward margin of the foot opening.

10 In testimony whereof I affix my signature.
FREDERICK A. BALLOU.

In testimony whereof I affix my signature.
ROGERS T. STAFFORD.
